CLAIM

The ornamental design for a sports bottle lid with straw and handle, as shown and described.

DESCRIPTION

FIG. 1 is a perspective view of a sports bottle lid with straw and handle showing my new design in a closed position; FIG. 2 is another perspective view of the sports bottle lid with straw and handle showing my new design in an open position;

FIG. 3 is a front view of the sports bottle lid with straw and handle of FIG. 1 shown in the closed position;

FIG. 4 is a back view thereof;

FIG. 5 is a right side view thereof;

FIG. 6 is a left side view thereof;

FIG. 7 is a top view thereof; and,

FIG. 8 is a bottom view thereof.

The broken lines depict portions of the a sports bottle lid with straw and handle that form no part of the claimed design.

1 Claim, 8 Drawing Sheets
